CASING OR ENCLOSURE FOR WATER SOFTENING APPARATUS

Filed June 7, 1948

UNITED STATES PATENT OFFICE

2,579,328

CASING OR ENCLOSURE FOR WATER
SOFTENING APPARATUS

Roberts Kitchener Lynes, Birmingham, England

Application June 7, 1948, Serial No. 31,507
In Great Britain May 3, 1948

5 Claims. (Cl. 312—237)

1

This invention relates to casings or enclosures for water softening apparatus and more particularly for water softening apparatus of the kind or type technically known as the "base exchange" type.

As is well understood water softening apparatus of the said type ordinarily incorporates a preferably cylindrical chamber for containing the charge of zeolitic or other granulated or powdered material employed in the softening process the said chamber having in association therewith a system of pipes or conduits and valve mechanism for controlling the water flow in the normal use of the apparatus and also such variations in the flow as are requisite from time to time for the performance of the flushing and draining operations involved in effecting the regeneration of the zeolite or other crystals contained in the cylindrical chamber.

It has heretofore been proposed to provide in combination with water softening apparatus of the kind or type aforesaid a casing or enclosure designed to accommodate the crystal containing chamber of the softening apparatus and the valve mechanism and those parts of the water inlet, outlet and other pipes or conduits incorporated in the installation which are contiguous to the said chamber and thereby to give to the apparatus a cabinet-like appearance.

As heretofore constructed the said casing or enclosure has comprised three parts or sections, namely, a main part or body section, a detachable cover for the upper end of the said main section and a base or plinth to which the body is attached by screws passed into lugs or brackets furnished on the base or plinth.

Ordinarily the said parts or sections are made from sheet metal the body section being formed by so bending a single sheet or plate of appropriate size as to produce therefrom a body structure of rectangular or substantially rectangular formation and comprising a front wall having two parallel side walls integral therewith and projecting rearwardly at right angles thereto, the rearwardly presented side of the body structure being open.

The said ordinary construction of the main part or body section of the casing is attended with the disadvantage that its bulk renders it inconvenient both for storage and transit and furthermore the charges for shipment, which are based, as is customary, on the space required for stowage, are heavy.

The present invention has for its object to provide an improved construction of cabinet-like

2

casing or enclosure to be used in combination with water softening apparatus of the kind with which the invention is concerned and whereby the disadvantages aforesaid attending the use of the ordinary construction of such casings or enclosures are obviated.

The invention is characterised in that the cabinet-like casing or enclosure combined with the water softening apparatus comprises a main part or body section the walls whereof instead of being integrally formed as heretofore are constituted by three separate panels constructed and adapted to be assembled as hereinafter described and which prior to their assembly can be packed and for convenience of storage and/or transit in a flat condition.

The invention further resides in the construction of the base or plinth provided in association with the said body section and the means combined with the plinth for the proper location relative thereto of the lower end of the chamber of the water softening apparatus and in other details of construction hereinafter described.

The invention will be further and more particularly described with reference to the accompanying drawings which illustrate a casing or enclosure in accordance with the invention in its application to water softening apparatus of the construction described in the specification of my co-pending application, Serial No. 793,561, filed December 23, 1947, now abandoned, for Letters Patent.

The parts comprising the casing or enclosure are shown in the drawings in the erected condition.

Figure 1 of the drawings represents the casing in front elevation, the softening apparatus to which it is applied being indicated in dotted lines only and more or less diagrammatically in the said figure.

Figure 2 is a plan of the same, one half of the casing being shown in horizontal section.

Figure 3 is a vertical section on the plane indicated by the dotted line 3—3, Figure 2, a portion of the main part or body section being broken away.

Figure 4 is a plan of the base or plinth shown apart from the casing.

Figure 5 represents a fragmentary portion of the upper part of the casing in sectional elevation, and

Figure 6 is a fragmentary sectional plan of one front corner of the casing.

Figures 5 and 6 are drawn to a larger scale than the other figures of the drawings.

The same numerals of reference indicate the same parts in the several figures wherein the softening chamber is denoted by the reference 8, the control unit associated therewith by the reference 9, and contiguous portions of the pipework of the installation by the reference 10.

In accordance with this invention the main part or body of the casing or enclosure comprises a front wall marked 11 and two side walls marked 11^a parallel with each other and at right angles to the front wall 11 each wall being constituted by a panel of plate or sheet metal of the appropriate dimensions to provide a casing which will accommodate the apparatus to be enclosed.

The vertical and horizontal marginal parts marked respectively 11^b and 11^c of each panel are inwardly bent or flanged so that the panels have a shallow dish-like formation and the flange 11^c which extends along the lower horizontal edge of each panel is formed with a part 11^d which is bent or turned downwardly in a vertical plane, as best seen in Figure 3, the said vertically depending parts 11^d providing for the location as hereinafter described of the body section on the base or plinth denoted generally by the reference 12 and shown separately in plan in Figure 4.

The flanges 11^b on the respective vertical edges of the panels or walls, 11, 11^a are adapted for the connection therewith of fillets, marked 13, 13^a, which, when the panels are assembled to form the casing or enclosure, constitute the vertical corners of the casing and give rigidity thereto and also serve to enhance the smart appearance of the casing, the fillets 13 at the front corners further serving for effecting the connection of the panels 11^a forming the side walls with the respective sides of the panel 11 which constitutes the front wall of the casing.

The said corner fillets 13, 13^a are preferably tubular and made from appropriate lengths of sheet or strip metal so bent that they have a quadrantal figure in cross section, as seen in Figures 2 and 6, their flat sides having a width equivalent, or approximately equivalent, to the width of the flanges 11^b of the vertical sides of the panels to which in the assembling of the parts they are fixed by pins 13^b, or rivets, any desired number of which may be employed, appropriately spaced apart, according to the length of the body section.

The base or plinth 12 aforesaid associated with the body of the casing is, as is best seen in Figure 4, of an open sided frame-like construction, the parallel arms or sides and the cross member which interconnects them at their front ends being of L or angle section, the vertical webs, marked 12^a, projecting upwards from the outer edges of the respective horizontal webs, marked 12^b, the distance between the inner faces of the vertical webs 12^a of the parallel side arms being such as to permit the location between them of the downwardly turned parts 11^d on the horizontal flanges 11^c on the lower ends of the panels 11^a of the respective side walls of the casing, and the depth of the said vertical webs 12^a of the plinth being such that when the main part or body of the casing is properly located thereon the horizontal flanges 11^c on the lower edges of the walls of the casing take a seating on the upper edges of the corresponding vertical webs 12^a of the plinth as is best seen in Figure 3.

The plinth 12 has in association therewith and disposed in a horizontal plane between its side arms, a circular band-like clip made in two parts or halves, marked 14, 14^a, the respective ends of

each part being bent laterally outwards to provide earpieces 14^b which are furnished with coincident holes or perforations for the passage therethrough of connecting screw bolts or pins 15 whereby the two parts of the clip may be detachably secured together.

The part or half 14 of the clip which is adjacent the front side or cross member of the plinth 12 is fixed to the plinth by soldering or otherwise securing its earpieces 14^b to the respective side arms of the plinth with its open side presented to the open side of the plinth.

This two part clip has an internal diameter appropriate for embracing the cylindrical chamber 8 of the softening apparatus when the plinth is applied thereto.

The top of the body or main part of the casing has a horizontal plate or platform 16 thereon which is furnished with an aperture 16^a through which the reduced or neck-like upper end of the softening chamber 8 projects, the said aperture 16^a preferably having an upwardly curved periphery which is seated on a grommet 17 of India rubber or other suitable non-metallic material arranged on the neck of the cylinder 8 below the underside of the said platform 16.

The aperture 16^a in the platform 16 is in axial alignment with the two part clip aforesaid associated with the base or plinth when the casing is applied to the softening apparatus.

The platform 16 is secured to the top of the main part or body of the casing by screw pins 18 passed through holes provided in the horizontal flanges 11^c aforesaid on the upper edges of the respective panels and corresponding holes in the platform.

The nuts 19 whereby the said screw pins 18 are secured are, preferably of the taper or conical formation shown and are, or may be, made of fibre or other suitable non-metallic material and adapted to constitute pegs for a locating engagement with coincident holes provided in inwardly turned parts 26^a on the lower edges of the depending rim or flange of a detachable top cover 20.

In applying the casing described to the softening apparatus the detachable part 14^a of the band-like clip associated with the plinth 12 is first detached from the fixed part 14 of the clip and the plinth is pushed up to the softening cylinder 8 so as to bring the fixed part 14 of the clip into position thereagainst, the detachable part of the clip 14^a being then re-connected to the fixed part and bolted up.

The screw cap 8^a whereby the upper end of the softening chamber 8 is ordinarily closed is temporarily removed and the main part or body of the casing is lowered down over the said chamber and the contiguous portions of the pipework 10 associated therewith until the downturned parts 11^d on the flanges 11^c on the lower horizontal edges of the panels engage within the vertical webs 12^a of the plinth, the said downturned parts 11^d on the respective side panels 11^a being appropriately notched for the accommodation of the earpieces of the fixed part 14 of the band-like clip.

When the body section of the casing is in the fully lowered position the engagement of its lower end with the plinth 12 and the engagement of the periphery of the aperture 16^a in the platform 16 at its upper end with the grommet 17 provided as aforesaid on the neck of the chamber 8 co-act to effect a very rigid holding of the casing in position on the chamber.

The assembling operation is completed by re-fixing the screw cap **8** on the chamber **8** and then placing the detachable cover **20** on the upper end of the main part or body of the casing whereon it is located by the peg-like nuts **19** aforesaid.

The front wall or panel **11** of the casing is provided with an aperture **11^e** appropriately located therein for gaining access to the control unit **9** mounted on the softening chamber **8**.

It will be appreciated that the parts of casings in accordance with the invention can, prior to their assembly for application to softening apparatus, be packed in a flat condition for convenience of storage or transit.

I claim:

1. A sectional casing for enclosing water softening apparatus of the type comprising an upright water treating chamber having a neck at its upper end and external piping, said casing comprising a plinth-like base section closed at the front and two sides and open at the rear for insertion at the front and sides of the lower end of said chamber, complementary front and rear clips to embrace the lower end of the chamber and having means for clamping them together against the chamber, one of said clip members being fixed to the sides of the base section, an upright body section designed to enclose the water softening chamber and piping and having front and side walls and being open at the rear to receive the chamber and piping, a top member fixed to the upper end of the body section and having an aperture therein to receive the neck on the chamber, and a cover section removably positioned on the top member and enclosing the upper end of the neck on the chamber.

2. A sectional casing for enclosing water softening apparatus of the type comprising a water treating chamber having a neck at its upper end and a removable cap therefor, and external piping, said casing comprising a plinth-like base section having secured thereto a clip member engageable with one side of the lower end of the chamber and a complementary clip member engageable with the other side of the lower end of the chamber, means for securing the clip members together and thereby clamp the lower end of the chamber between them, an upright body section mounted on the base section and designed to enclose the body of the chamber and its external piping, a top member fixed to the upper end of the body section and having an opening therein to receive the neck of the water treating chamber, and a cover section

removably mounted on said top member and enclosing the cap on the water treating chamber.

3. A sectional casing as defined in claim 2, including projections fixed to said top member and extending upwardly therefrom, and wherein said cover section is provided with inturned flanges to rest on said top member and having apertures therein to receive said projections and thereby position the cover section on the body section of the casing.

4. A sectional for enclosing water softening apparatus of the type having an upright water treating chamber and external piping, comprising a plinth-like base section having upturned front and side flanges, an upright body section designed to enclose the chamber and piping and having front and side walls provided at their lower edges with flanges which are turned inwardly to rest on the respective flanges on the base section and turned downwardly to engage the inner sides of the respective flanges on the base section, a top plate fixed to the upper end of the body section and having an aperture therein for extension of the upper end of the water treating chamber therethrough to its upper side, and a cover section having inturned flanges to rest removably on said top plate and space the cover section above the upper end of said chamber.

5. A sectional casing as defined in claim 4, wherein said body section comprises front and side walls having flanges along their adjacent edges which are inturned and lie in right angular relation at the respective corners of the body section, and including corner fillets of quadrangular cross-section forming right angular flanges thereon which are fitted between and secured to the flanges of the front and side walls at the respective corners of the body section.
